KNEE STRUCTURE FOR ARTIFICIAL LEG

George Guzey, Valdosta, Ga., assignor of one-half to
Anna Oalsavick, Monessen, Pa.

Application July 16, 1957, Serial No. 672,145

4 Claims. (Cl. 3—28)

The present invention relates to knee structures for artificial legs, and more particularly to such structures which closely simulates the movement of a natural knee.

The primary object of the invention is to provide a knee structure for artificial legs which maintains a relatively even tension on the joint throughout the bending movement thereof.

Another object of the invention is to provide a knee structure for artificial legs in which the tension applied to the joint can be quickly and easily adjusted to accommodate the movement of the user.

A further object of the invention is to provide a knee structure for artificial limbs which is extremely light in weight and which can be added to an artificial limb without increasing the weight thereof.

A still further object of the invention is to provide a knee structure of the character described above which is inexpensive to manufacture, simple to use, and which can be adjusted with a minimum of training and equipment.

Other objects and advantages will become apparent in the following specification when considered in the light of the attached drawings, in which:

Figure 1 is a fragmentary side elevation of the invention.

Figure 2 is an enlarged fragmentary vertical cross-section taken through the knee joint from front to rear.

Figure 3 is a fragmentary vertical cross-section taken along the line 3—3 of Figure 2, looking in the direction of the arrows.

Figure 4 is a semi-diagrammatic view illustrating the knee joint in erect position.

Figure 5 is a view similar to Figure 4 illustrating the knee joint in a partially bent position.

Figure 6 is a perspective view of the band support bracket removed from the leg.

Figure 7 is an enlarged fragmentary horizontal cross-section taken along the line 7—7 of Figure 2, looking in the direction of the arrows.

Figure 8 is a side elevation shown partly broken away and in section of a modified form of knee joint.

Figure 9 is a fragmentary enlarged front elevation of a detail of the structure illustrated in Figure 8.

Figure 10 is an enlarged fragmentary vertical cross-section taken along the line 10—10 of Figure 8, looking in the direction of the arrows.

Referring now to the drawings in detail wherein like reference characters indicate like parts throughout the several figures, the reference numeral 20 indicates generally a knee joint structure of an artificial leg.

The knee structure 20 is connected between a hollow lower leg member 21 and a hollow upper leg member 22. The lower leg member 21 has its upper end connected to the lower end of the upper leg member 22 by means of a pair of pivot members 23, 24 arranged in axially aligned horizontal relation on opposite sides of the upper and lower leg members 22, 21, respectively. The leg members 21, 22 and their pivot connections 23,

2

24 are of conventional design and provide a pivotal knee action for the user.

A mounting bar 25 is positioned within the hollow lower leg member 21 and is horizontally arranged extending from front to rear thereof, as shown in Figure 2. The mounting member 25 has depending flanges 26, 27 on its opposite ends which are secured to the lower leg member 21 by securing elements 28.

A resilient headed bushing 29 extends upwardly through the forward end of the mounting bar 25 and has a mounting bolt 30 extending therethrough for vertical sliding movement. A nut 31 is threaded onto the lower end of the mounting bolt 30 and engages against the head 29a of the headed bushing 29. The mounting bolt 30 is forwardly offset at 32 and is supported for sliding movement in an upright position by a bracket 33 secured to the lower leg member 21 by securing element 34.

A resilient bushing 35 encompasses the bolt 30 and spaces the bracket 33 therefrom. A head member 36 is threaded over the upper end of the bolt 30 and is locked in position thereon by a lock nut 37. A cushion 38 is secured to the upper end of the head member 36 by means of securing elements 39.

An angular bracket 40 is mounted on the lower end of the upper leg member 22 by means of securing elements 41 and has a cushion 42 secured to its lower face by means of securing elements 43. The cushions 38 and 42 are vertically aligned, engage together to move the mounting bolt 30 downwardly and to brace the lower leg member 21 and the upper leg member 22 in straight position.

The head 36 serves as a limit for the pivotal movement of the lower leg member 21 with respect to the upper leg member 22 and can be vertically adjusted on the upper end of the mounting bolt 30 as required.

A coil spring 44 has its lower end engaged against the mounting bar 25 encompassing the headed bushing 29 and has its upper end engaged against a spring saddle 45 through which the mounting bolt 30 extends. An elongated arm 46, as shown in Figure 7, is provided with a bore 47 adjacent one end thereof through which the mounting bolt 30 extends.

The elongated arm 46 is engaged against the spring saddle 45 and secured thereagainst by a lock nut 48. The elongated arm 46 is provided with upstanding ears 49 on opposite sides thereof which engage the nut 48 and restrain it against rotation with respect to the arm 46.

The mounting bolt 30 is resiliently supported by the spring 44. The spring 44 is relatively stiff and assists in absorbing the shock of bending the knee and walking.

A generally rectangular bar 50 is arranged in vertically spaced relation above the arm 46 and has a pair of elongated bolts 51 extending downwardly therethrough and through the arm 46. The bolts 51 are arranged in spaced parallel relation and have elongated sleeve type nuts 52 threaded engaged thereon. The nuts 52 extend through the arm 46 to guide the bolts 51 therethrough.

The nuts 52 each are provided with flanges 53 at their lower ends and coil springs 54 engage against the flanges 53 at one end and the arm 46 at the other end in encompassing relation to the nuts 52. Another coil spring 55 is positioned between the bar 50 and the arm 46 in encompassing relation to the bolt 51 and nut 52 furthest removed from the mounting bolt 30. Mounting loops 56 are pivotally secured to opposite ends of the bar 50, for reasons to be assigned.

A transverse support 57 is provided with depending end portions 58 and is secured in transverse horizontal position within the upper leg member 22 spaced substantially above the pivots 23, 24. The support 57 is

detachably secured to the upper leg member 22 by means of securing elements 59.

An arcuate support member 60 is positioned centrally on the support 57 and extends perpendicularly thereto. The support 57 is welded to the bracket 60 intermediate the opposite ends thereof. Aligned ears 61, 62 extend upwardly from the side edges of the bracket 60 adjacent the opposite ends thereof and have a roller 63 journaled therein at each end of the bracket 60.

The rollers 63 are positioned on the upper side of the bracket 60 as can be best seen in Figure 6. A band of friction material 64 is secured to the bracket 60 between the rollers 63 by any suitable means such as adhesives, rivets, or the like.

A steel band 65 is threaded through the loops 56 and secured to itself as at 66 to attach the steel band to the loops 56. The opposite end of the steel band 65 has an upstanding flange 67 formed thereon.

A second steel band 68 has one end thereof threaded through the loop 56 opposite the band 65 and secured to itself at 69 to connect the band 68 to the loop 56. The opposite end of the steel band 68 is provided with a perpendicularly extending flange 70 arranged adjacent to the flange 67.

A bolt 71 adjustably connects the flanges 67, 70, as seen in Figure 2, to form the bands 65, 68 into a single unit when considered with the bar 50. The bands 65, 68 are trained over the roller 63 and bear against the friction material 64 so that the movement of the bands 65, 68 with respect to the bracket 60 will be retarded.

In knee structures for artificial legs as previously constructed, the tension of the joint increased as the bending increased so that sitting without releasing the tension on the knee became virtually impossible, and the wearer of the artificial leg became embarrassed. The action of releasing the tension on the springs of the conventional leg structures is in itself quite embarrassing to most persons and calls attention to the fact that an artificial limb is being worn.

In the instant invention, the tension of the springs holding the leg straight are greatest when the leg is straight, and least when the leg is completely bent so that the act of sitting and rising is performed naturally without embarrassment to the wearer or the leg.

In the use and operation of the invention, the springs 54, 55 and 44 have their tension adjusted by adjusting the bolts 51 and nut 31 so that sufficient friction exists between the bands 65, 68 and the friction material 64 to hold the leg member 21 straight with respect to the leg member 22 under normal conditions. As the leg is bent during a sitting act the cushion 42 moves away from the cushion 38 allowing the mounting bolt 30, arm 46, and bar 50 to move upwardly so as to loosen the bands 65, 68 which then slide across the friction material 64 and the roller 63 and allows the bending about the pivots 23, 24 to take place.

As can be seen from the semi-diagrammatic figures, Figure 4 and Figure 5, the bracket 60 moves about the pivot points 23, 24 toward the bar 50 so as to shorten the distance therebetween and relieve a portion of the tension on the springs 54, 55. Obviously the greater the degree of bending of the upper leg member 22 with respect to the lower leg member 21, the less tension which will be applied by the springs 54.

Referring now to Figures 8 through 10, a modified form of the invention is illustrated wherein the amputation of the natural limb has been made in, or slightly above the knee joint so that there is no upper leg member similar to the upper leg member 22 illustrated in the preferred form of the invention.

The modified form of the invention includes a V-joint 20a which is positioned between the lower leg member 21a and a socket member 22a arranged to receive the stump 72 which has been amputated slightly above the knee joint. The socket member 22a is secured to the

stump 72 in a conventional manner using straps 73.

The socket member 22a is provided with a pair of hinge members 74, 75 arranged on opposite sides thereof and secured by pivots 23a to the upper end of the lower leg member 21a. The pivots 23a, only one of which is shown, are spaced apart laterally in aligned relation with their axes extending transversely of the leg member 21a in the same manner as the pivots 23, 24 in the preferred form of the invention.

A mounting plate 25a identical to the mounting bar 25 is mounted in the lower leg member 21a in the identical manner as the mounting of the mounting bar 25. A mounting bolt 30a identical to the mounting bolt 30 carries a bar 46a of the same construction as the arm 46. The head 36a secured to the upper end of the mounting bolt 30a is provided with a slot 76 extending centrally downwardly therethrough, for reasons to be assigned.

The upper end of the head 36a is provided with a pair of cushion pads 38a and 38b secured in horizontally aligned relation on opposite sides of the slot 76. The socket member is provided with a pair of cushion pads 42a arranged to engage the cushion pads 38a, 38b when the stump 72 is aligned with the lower leg member 21a.

A plate 50a is resiliently mounted on the bar 46a by bolts 51a in the same manner that the bar 50 is mounted on the arm 46. An arcuate bracket 60a is arranged with its concave surface upwardly and provided with rollers 63a adjacent the opposite ends of the lower face thereof.

The bracket 60a is integrally connected to the plate 50a by webs 77, 78 extending between the respective opposite side edges thereof in the medial area thereof. The lower convex face of the bracket 60a is provided with a friction band 64a similar to the band 64 on the bracket 60.

A flexible steel band 65a is connected at 66a to the forward edge of the socket member 22a and at 69a to the rear edge thereof. The band 65a may be made in one piece, as illustrated in Figure 8, or in two pieces, as illustrated in the preferred form of the invention illustrated in Figure 2. The band 65a extends beneath the bracket 60a in contact with the friction member 64a and the roller 63a.

The action of the knee structure 20a is identical to the action of the knee structure 20 in that the tensions resisting bending thereof are greatest when the knee is straight and least when the knee is fully bent.

The band 65a slides on the bracket 60a and is retarded in its movement thereover by the friction material 64a. Tension on the plate 50a maintains the frictional relation between the band 65a and the friction material 64a. As the knee is bent to its fullest extent, the frictional contact is lessened sufficiently to permit easy movement of the knee joint.

The band 65a, when the knee is straight, extends through the slot 76 in the head 36a, as illustrated in Figure 9.

While, in both the preferred form of the invention and the modification, a single bracket and band arrangement have been illustrated, it should be understood that additional brackets and bands may be incorporated into the knee structure without departing from the concepts described above.

Having thus described the preferred embodiments of the invention, it should be understood that numerous other structural modifications and adaptations may be resorted to without departing from the scope of the appended claims.

What is claimed is:

- An artificial limb comprising a pair of vertically spaced members, means extending transversely between said members pivotally securing said members together, flexible friction means extending between said members for restraining the pivotal movement between said members, and spring biased means cooperatively engaging said flexible friction means to vary the restraining effect

of said flexible friction means, with said flexible friction means having its greatest restraining effect when said vertically spaced members are in aligned relation.

2. A device as claimed in claim 1 wherein the means extending between said members includes a flexible band associated with said spring biasing means, and a friction bracket over which said band moves during pivotal movement of said vertically spaced members.

3. A device as claimed in claim 2 wherein said bracket is positioned in the upper of said vertically spaced members and said spring biasing means is positioned in the lower of said vertically spaced members.

4. A device as claimed in claim 2 wherein said bracket is positioned in said lower member and is carried by said spring biasing means.
